SPECTACLE FRAME

Harry Weissman, Great Neck, N.Y. (½ Paramount Optical Mfg. Corp., 60-06 39th Ave., Woodside, N.Y. 11377)

Filed Nov. 26, 1965, Ser. No. 88,227

Term of patent 7 years

(Cl. D57—1)

Fig. 1

Fig. 2

Fig. 3

FIG. 1 is a top plan view of a spectacle frame showing my new design.

FIG. 2 is a front elevational view thereof.

FIG. 3 is a side elevational view thereof.

The dominant features of my design reside in the portions shown in full lines.

I claim:

The ornamental design for a spectacle frame, as shown and described.
